Patented Nov. 9, 1915.

UNITED STATES PATENT OFFICE.

EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

SEATING.

1,159,356.

Specification of Letters Patent.

Patented Nov. 9, 1915.

Application filed July 24, 1908. Serial No. 445,087.

To all whom it may concern:

Be it known that I, EDWARD G. BUDD, a citizen of the United States, and a resident of Philadelphia, in the county of Philadelphia and State of Pennsylvania, have invented certain new and useful Improvements in Seating, of which the following is a specification.

This invention is directed to the improvement of the construction of seats of the type commonly employed in railway cars and has reference more particularly to the seat-ends and arm-rests of seats for this and similar uses.

15 In the manufacture of car-seats it has been found highly desirable to employ metallic parts to a very large extent in order that the structure may be fire-proof, and to secure greater strength. In accordance 20 with this method of manufacture, a seat-end has been provided for the aisle end of a car-seat formed of two sheet-metal plates pressed to the desired shape and secured together at their edges with open space between them; and an arm-rest has been secured upon the upper edge of this seat-end, this arm-rest being formed of one or more 25 metallic parts and having a downwardly extending projection on the bottom thereof adapted to coact with the upper edge of the seat-end to position the arm-rest thereon. I have found that it is undesirable to so construct the arm-rest that the upper surface thereof is of metal since the arm of an occupant of the seat is frequently in contact with this surface and would be chilled if metal were employed at this point. On the other 30 hand, it is desirable to employ metal in the construction of the arm-rest in order to secure the advantages of increased strength, low manufacturing cost and fire-proof construction. I have therefore provided an improved form of arm-rest in which the material of the upper surface is non-metallic.

45 Preferably material is employed for this purpose which may be molded into the desired form so as to give to the arm-rest a graceful, smooth contour and one which will be most conducive to the comfort of the occupant of the seat. Various non-metallic materials may be employed for this purpose which are poor conductors of heat and which may be molded to the desired form; thus rawhide and hard fiber are well suited 50 for this purpose as is also a specially pre-

pared leather which may be molded into form and which becomes quite hard. Any one of these materials may be molded to the proper shape so as to form a shell which while being comparatively thin, possesses ample strength. This stiff, non-metallic shell may form the upper half of the arm-rest, its edges being secured to the lower half which for the purposes above pointed out is preferably made of sheet-metal. This 60 molded shell may be made of such strength that it need not be reinforced by a metallic part but if desired the arm-rest may be constructed in somewhat the same manner as has been done heretofore, having the upper 65 part of metal and a thin, stiff non-metallic covering may be applied over this upper metallic part; in this case the non-metallic material is preferably molded into form and may be glued to the sheet-metal part which 70 supports it.

Another feature of my invention resides in the provision of an improved construction of arm-rest, this consisting of two side plates of sheet-metal and a curved top piece 80 the edges of which interlock with and are secured to the upper edges of the side plates. With this form of arm-rest a seat-end may be employed so constructed as to provide side plates having integral upwardly extending 85 projections entering within the arm-rest and coacting with the side plates thereof and bolts may be employed for securing the arm-rest to these projections.

I have illustrated the preferred embodiment of my invention in the accompanying drawings in which—

Figure 1 is an elevation of the seat-end and arm-rest, broken away and sectioned in part; Fig. 2 is a sectional view on line 2—2 of Fig. 1, Fig. 3 is a similar view on line 3—3 of Fig. 1, and Fig. 4 is a view similar to Fig. 2 illustrating a modification.

Referring to these drawings, 1 indicates a seat-end of the general type now employed consisting of two sheet-metal plates pressed to the desired form and secured together at their edges with open space between them, and 2 indicates an arm-rest which is secured upon the upper edge of this seat-end. At 100 each end of the upper edge of each of the plates of the seat-end is an integral, upwardly extending projection 3. Between the projections 3 on each plate two inwardly turned flanges 4 are provided upon the upper 105 110

edge of the plate and between these flanges 4 is a similar flange 5, the latter being spaced apart from the flange 4 by a short distance as shown in Fig. 1. The arm-rest consists of two sheet-metal side plates 6 and 7 and a sheet-metal top piece 8. On the lower edge of each of the side plates 6 and 7 is an inwardly extending flange 9 adapted to rest upon one of the flanges 5 of the seat-end. The flanges 9 are at the central portions of the lower edges of the side plates 6 and 7 only and at the ends of those edges the metal of the side plates extends downwardly a slight distance so that it overlaps the seat-end. At its upper and end edges each of the plates 6 and 7 is provided with an inwardly turned flange 9' and a series of projecting teeth 10 at the edge of this flange. The top piece 8 is of sheet-metal pressed to the desired form to provide flanges 11 adapted to rest upon the flanges 9' of the side pieces, and downwardly extending flanges 12 at the edges of the flanges 11. In the flanges 12 are openings corresponding in size and position to the projections 10 on the side plates 6 and 7 through which those projections extend to hold the top piece rigidly in position upon the side plates. The side plates and top piece thus constructed are assembled in the manner indicated and are positioned upon the seat-end with the projections 3 extending within the arm-rest and lying alongside the side plates thereof and the flanges 9 resting upon the flanges 5 of the seat end, spacing sleeves 13 being first inserted between each pair of projections 3. This being done a bolt 14 is passed through openings in the side plates 6 and 7 and the projections 3 and through the spacer 13. The end of this bolt is then turned over so as to rivet these parts firmly together. By this construction an arm-rest is provided consisting of a small number of sheet-metal parts which may be readily manufactured at low cost and quickly assembled; this arm-rest, being of metal, is fire-proof and the construction is such that great strength is secured.

I have found that it is quite undesirable that the upper surface of an arm-rest should be of metal on account of the fact that the arm of an occupant of the seat contacting with the upper surface of the arm-rest would be chilled thereby. I have, therefore, provided an arm-rest so constructed that the upper surface is of non-metallic material which is a poor conductor of heat.

In Figs. 1, 2 and 3, I have shown a thin, stiff shell 15 of non-metallic material applied over the metallic top piece 8 of the arm-rest; this shell is made of a material which may be molded to the desired form and then hardened so that it will retain this shape, and which is of poor heat-conductivity. Thus, I may make shell 15 of moldable hard

fiber or raw-hide or I may employ canvas or leather specially prepared so that it may be molded into form and then hardened to retain its shape. When a top piece of metal is employed for the arm-rest, as the part 8 above referred to, the non-metallic shell 15 may be molded to the shape of this top piece and glued to it. The material of the shell 15 may be such that a smooth surface is provided on the top of the arm-rest so that the completed structure is of an attractive appearance and it will be seen that as this surface is of non-metallic material, chilling of the arm of the occupant of the seat by contact with the metal, is avoided.

In Fig. 4 I have illustrated a modification of my invention in which the metallic top piece of the arm-rest is omitted and the stiff, non-metallic shell forms the top piece of the arm-rest. This shell is constructed in the manner above described except that it may be made somewhat thicker to give it additional strength and its edges are formed to coact with the side members of the arm-rest 6. Shell 16 of Fig. 4 is so provided with downwardly extending flanges at its edges having openings to receive the projections 10 on the side plates 6 and 7 of the arm-rest.

Having described my invention what I claim as new therein and desire to secure by Letters Patent of the United States is:—

1. In seating, the combination of a seat-end consisting of two parallel sheet-metal plates secured together and having pairs of oppositely-disposed projections extending upwardly from the ends of the upper edges thereof, and laterally-disposed flanges between said projections, and a hollow arm-rest having a top and side-plates and lower laterally-disposed flanges on said side-plates resting on said plate flanges, said projections extending within said arm-rest through the bottom thereof and lying along side the side plates of said arm rest, and means for securing together said seat-end plates and arm rest at the said projections of said plates, substantially as set forth.

2. In seating, the combination of a seat-end consisting of two parallel sheet-metal plates secured together and having pairs of oppositely-disposed projections extending upwardly from the ends of the upper edges thereof, and laterally-disposed flanges between said projections, and a hollow arm-rest having a top and side-plates and lower laterally-disposed flanges on said side-plates resting on said plate flanges, said projections extending within said arm-rest through the bottom thereof and lying along side the side plates of said arm-rest, a spacer between the projections of each pair, and a bolt passing through each spacer and adjacent projections and arm-rest members, to secure the arm-rest to the seat-end, substantially as set forth.

3. The combination of a seat-end consisting of two parallel sheet-metal plates pressed into form and secured together, said plates having pairs of opposite, integral, upwardly extending projections thereon, a hollow arm-rest formed of two parallel, substantially flat, sheet-metal side-plates having inwardly turned flanges at their upper edges, and a top-piece having its ends turned downwardly at the ends of the side-plates to close the ends of the arm-rest and having flanges at its lateral edges which are secured to the flanges on the side-plates, said projections entering within said arm-rest, and means for securing the arm-rest to said projections, ¹⁵ substantially as set forth.
- 5
- 5 extending projections thereon, a hollow arm-rest formed of two parallel, substantially flat, sheet-metal side-plates having inwardly turned flanges at their upper edges, and a top-piece having its ends turned downwardly at the ends of the side-plates to close the ends of the arm-rest and having flanges at its lateral edges which are secured to the flanges on the side-plates, said projections entering within said arm-rest, and means for securing the arm-rest to said projections, ¹⁵ substantially as set forth.
- 10

This specification signed and witnessed this 21st day of July, 1908.

EDWARD G. BUDD.
